DISTRIBUTING DEVICE FOR REELING MECHANISM.

1,404,853.

Specification of Letters Patent.

Patented Jan. 31, 1922.

Application filed January 24, 1919. Serial No. 272,869.

To all whom it may concern:

Be it known that I, JOHN ALLEN HEANY, a citizen of the United States of America, residing at New Haven, in the county of New Haven and State of Connecticut, have invented certain new and useful Improvements in Distributing Devices for Reeling Mechanism, of which the following is a specification.

10 This invention relates to traversing or distributing devices for winding mechanism and has for its object to provide an improved device of this general nature in which the winding operations performed on a series 15 of reels can be controlled by a single distributing device common to all the reels.

With this and other objects in view, the present invention consists in the provision of a traversing device having a distributing 20 rod reciprocable along its own length and provided with a series of guide members for regulating the distribution of the windings on a series of reels mounted to rotate on an axis substantially parallel to the rod. In 25 order to reciprocate the rod, I provide a threaded portion thereon with which a correspondingly threaded ratchet wheel is arranged to cooperate, the ratchet wheel being held against lateral movement in order to 30 reciprocate the rod with relation thereto.

The means for rotating the ratchet wheel preferably takes the form of a double-acting pawl that is pivotally mounted intermediate its ends and adapted to be reversed so that 35 either end may be brought into operative engagement with the ratchet wheel to rotate the wheel in the corresponding direction. In order to reverse the pawl and thereby reverse the direction of travel of the distributing rod at either limit of its travel, tripping members are mounted directly on the distributing rod and arranged to be brought 40 into engagement with a pawl reversing member to throw the pawl from one operative 45 position to the other at the proper stages in the operation.

In the drawing, in which a preferred embodiment of the invention is illustrated,

Fig. 1 is a view in perspective of a device 50 embodying the invention; and

Fig. 2 is a perspective view of a pawl and ratchet mechanism used in the device.

The traversing mechanism disclosed embodies a distributing rod 1 of any suitable 55 length for directing the distribution of the

windings on the desired number of reels 2 mounted on a rotatable shaft 25. The distributing rod 1 is provided with guide fingers 3 arranged in pairs and so disposed as to engage the wires, threads, or other filamentary elements 4 and distribute them in regularly arranged windings on the receiving reels 2.

The distributing rod 1 is reciprocably mounted at either end in suitable bearings, 65 such as are shown at 5, mounted in brackets 6, carried by the framework 7 of the machine, delivering the wires or the like 4 that are to be wound. It will be seen that a pair of such brackets 6 are shown at one end of 70 the machine between which a ratchet wheel 8 is mounted on a threaded portion 9 of the distributing rod 1. The ratchet wheel 8 has threaded engagement with the corresponding portion of the distributing rod, 75 and it will be seen that, if the ratchet wheel is rotated and held against lateral movement by the bracket members 6, the rod 1 is given a longitudinal movement, the direction of movement depending upon the direction 80 of rotation of the ratchet wheel.

In order to rotate the ratchet wheel, a double-acting pawl 10 is loosely pivoted on an arbor 11 in turn mounted to rock in bearings provided by one end of the pair of 85 bell-crank levers 12 fulcrumed on the rod 1 in flanking relation to the interposed ratchet wheel 8. The arbor 11 is provided with downwardly projecting actuating lugs 21 affixed thereto adjacent the outer faces of 90 the bell-crank levers 12, and is further provided with a weight 13 and a pawl reversing finger 14 so that, when the arbor 11 is rocked to throw the weight to one side or the other of the vertical plane by a corresponding 95 movement of the actuating lugs 21, the pawl reversing finger 14 will move to the corresponding end of the slot 15 in the pawl 10 to cause the adjacent end of the pawl to assume operative engagement with the 100 toothed periphery of the ratchet wheel 8.

Driving means for the pawl 10 comprises a link or pitman 16 which serves to connect the other extremity of the bell-crank levers 12 with a crank 17 formed on the end 105 of a shaft 18 rotatably mounted in a bearing 19 and driven by a sprocket 20 from any suitable source, such as the reel-carrying shaft 25. As the bell crank levers 12 and the pawl 10 are oscillated by the motion of the 110

pitman 16, the pawl 10 steps the ratchet 8 around in the direction determined by whichever end of the pawl is operatively engaged with the ratchet wheel.

5 The consequent movement of the rod 1 in one or the other direction along its length causes the guide fingers 3 to distribute the windings of the wires 4 in a regular manner along the surface of the last previous layer.

10 When the limit of travel has been reached in either direction and the last winding put in place along the inner face of one end of the reels, the pawl 10 is reversed in position by the engagement with one or the 15 other of the reversing lugs 21 with one of the tripping lugs 22 carried by the distributing rod 1, whereupon the direction of travel of the rod is reversed and the series of windings distributed across the face of 20 the coils in the opposite direction. When this layer of windings has in turn been completed, the remaining tripping finger 22 on the rod 1 will engage the corresponding reversing lug 21 and again reverse the direction of travel of the distributing rod, and 25 this action is automatically repeated with each arrival of the distributing rod at the limit of its travel in either direction, as will be obvious.

30 What I claim is—

1. A traversing mechanism comprising: a reciprocable guide rod having a threaded portion, a ratchet wheel mounted on said rod in operative engagement with said 35 threaded portion, a reversible pawl arranged to rotate the ratchet wheel in either direction to thereby reciprocate the rod, means for operating the pawl, and means carried by said reciprocable guide rod for 40 reversing the pawl as the rod reaches its limit of movement in either direction.

2. A distributing device for reeling mechanism comprising: a reciprocable distributing rod having a series of guiding fingers 45 arranged to distribute the windings on a series of reels, a ratchet wheel secured against lateral movement and having threaded engagement with said rod, a reversible actuating pawl arranged to rotate 50 the ratchet wheel in either direction to thereby reciprocate the rod, means for operating the pawl, and means carried by said reciprocable guide rod for reversing the pawl as the rod reaches its limit of movement in either direction.

3. A distributing device for reeling mechanism comprising: a reciprocable distributing rod having a series of guiding fingers thereon arranged to distribute the windings 60 of a series of reels, said rod having a threaded portion, a ratchet wheel secured against lateral movement and mounted on said rod in operative engagement with said threaded portion, a reversible actuating pawl arranged to rotate the ratchet wheel alter-

nately in opposite directions to thereby reciprocate the rod, means for operating the pawl, a pawl reversing member, and tripping members carried by said rod and arranged to engage said pawl reversing member and reverse said pawl when the rod reaches its limit of movement in either direction.

4. A distributing device for reeling mechanism comprising: a reciprocable distributing rod having a series of guiding fingers arranged to simultaneously distribute the windings of a series of reels, said rod having a threaded portion, a ratchet wheel secured against lateral movement and mounted on 80 said rod in operative engagement with said threaded portion, a double-acting pawl pivoted intermediate its ends and arranged to be tilted in opposite directions to bring either end into engagement with said ratchet, means for operating the pawl, a weight for holding the pawl in either operative position, and means for moving the weight to tilt the pawl from one to the other operative position as the rod reaches its limit of travel in 90 either direction.

5. A distributing device for reeling mechanism comprising: a reciprocable distributing rod having a series of guiding fingers arranged to simultaneously distribute the 95 windings of a series of reels, said rod having a threaded portion, a ratchet wheel secured against lateral movement and mounted on said rod in operative engagement with said threaded portion, a double-acting pawl pivoted intermediate its ends and arranged to be tilted in opposite directions to bring either end into engagement with said ratchet, means for operating the pawl, a weight for holding the pawl in either operative position, and means carried by the distributing rod for moving the weight to tilt the pawl from one to the other operative position as the rod reaches its limit of travel in either direction.

6. A distributing device for reeling mechanisms comprising; a reciprocable distributing rod having a series of guiding fingers arranged to simultaneously distribute the windings of a series of reels, said rod having a threaded portion, a ratchet wheel secured against lateral movement and mounted on said rod in operative engagement with said threaded portion, arms pivoted on said rod on either side of said ratchet, an arbor pivoted in the ends of said arms adjacent the 115 periphery of said ratchet, a double-acting pawl pivoted intermediate its ends on said arbor and adapted to be tilted in opposite directions to bring either end into engagement with said ratchet, a pawl reversing member carried by said arbor and adapted to be 120 swung from one to the other side thereof to thereby tilt the pawl from one to the other operative position, and means for moving the weight to tilt the pawl from one to the 125 130

other operative position as the rod reaches its limit of travel in either direction.

7. A distributing device for reeling mechanisms comprising: a reciprocable distributing rod having a series of guiding fingers arranged to simultaneously distribute the windings of a series of reels, said rod having a threaded portion, a ratchet wheel secured against lateral movement and mounted on said rod in operative engagement with said threaded portion, arms pivoted on said rod on either side of said ratchet, an arbor pivoted in the ends of said arms adjacent the periphery of said ratchet, a double-acting pawl pivoted intermediate its ends on said

arbor and adapted to be tilted in opposite directions to bring either end into engagement with said ratchet, a pawl reversing member carried by said arbor and adapted to be swung from one to the other side thereof to thereby tilt the pawl from one to the other operative position, reversing lugs attached to said arbor on either side of said ratchet, and tripping members carried by said distributing rod and arranged to engage said reversing lugs to swing said weight and tilt said pawl from one to the other operative position as the rod reaches the limit of travel in either direction.

JOHN ALLEN HEANY.
